REFRIGERATING APPARATUS

Lewis W. Eggleston, Detroit, Mich., assignor to
 Detroit Lubricator Company, Detroit, Mich., a
 corporation of Michigan

Application February 17, 1933, Serial No. 657,168

15 Claims. (Cl. 62—101)

My invention relates to new and useful improvements in a refrigeration system, and has for an object the provision of a means for circulating a cooling medium through a region or space to be cooled.

Another object is to provide means to regulate the cooling effect produced by the circulating medium.

Another object is to provide means for abstracting heat from the circulating medium.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated a preferred embodiment of my invention, in which drawings—

20 Figure 1 is a top plan view of an apparatus embodying my invention, having certain of the insulating material broken away and having the top closure or cover member removed;

25 Fig. 2 is a view in section on the line 2—2 of Figure 1, showing the cover or closure member in place and also having part of the insulating material broken away;

30 Fig. 3 is a detail view in vertical central section of a control means for use in the system; and

Fig. 4 is a detail view partly in vertical central section of another form of control means.

Referring to the drawings by characters of reference, 1 designates, generally, a box or container for receiving material to be cooled or refrigerated. The container 1 is preferably substantially rectangular and is provided with heavily insulated front and rear walls 2, 3, end walls 4, 5, and bottom wall 6. The insulating medium 40 may be of any well-known and desired material which will prevent transmission of heat. The top of the container 1 is preferably provided with a cover or closure member 7, which is also heavily insulated and which is provided at its periphery 45 with a series of shoulders or steps 8 cooperating with similar shoulders or steps defining the top faces of the walls 2, 3, 4, and 5. The container 1 is provided with a metal liner 9 having a bottom wall 10 from which rise front and rear walls 11, 12, and end walls 13, 14. The walls 11, 12, 13, and 14 terminate at their top ends or edges in a laterally extending, continuous flange 15 which is out-turned and seats upon the lower-most step or shoulder 8. The inside face of the 55 cover member 7 is also provided with a metal

liner 16 which seats at its periphery on the flange 15. Positioned within the interior of the container 1 and preferably substantially centrally thereof, there is a refrigerant medium receiving casing or chamber 17 which is of metal such, for example, as copper or other good heat conducting material. The casing 17 has a bottom wall 18 which is supported upon suitable heat insulating material 19 supported on the bottom liner wall 10. The casing 17 has front and rear walls 10 20, 21, and side walls 22, 23, which extend upwardly from the bottom wall 18 and which terminate substantially at the cover liner 16 but slightly spaced therefrom.

Within the interior of the container 1 there 15 is a control device or header member 24, to be described, which serves to control the flow of the refrigerant medium through closed circulatory conduit systems 25 and 26, which are substantially identical, and serve to cool or abstract 20 heat from the interior of the container 1 and particularly the chambers 27, 28, respectively. Each of the systems 25 and 26 includes a pipe or tubular member, preferably of copper and semicircular in transverse cross section, having 25 its ends secured to and communicating with the control device 24, such that the control device together with each tubular member provides a continuous flow conduit. The tubular member 30 of the system 25 has a rearwardly and downward inclined leg or portion 29 which extends along and is in intimate heat transmitting relation with the side wall 22. The portion 29 is rigidly secured to the wall 22, preferably by soldering the same thereto, which also aids in heat transfer 35 between the portion 29 and the wall 22. The portion 29 extends rearwardly to the liner wall 12, where it is turned to provide a rear portion 30 extending along the rear wall 12. The junction between the portions 29 and 30 defines the 40 low point or portion of the system, the portion 30 being inclined slightly upward and terminating at the end or side wall 13. At the side wall 13 the tubular member is turned to lie therealong, as at 31, at a continuation of the upward 45 inclination of the portion 30. This side or end portion 31 of the tubular member extends forward to the front liner wall 11, where it is turned to extend therealong, as at 32, and also at an upward inclination. The portion 32 which extends along the wall 11 is turned inwardly, as at 33, substantially at the midportion of the front wall 11 and terminates at the control device 24 to which it is connected. The portions 30, 31, and 32 are rigidly secured in intimate heat 50 55

transmitting relation to the liner walls 12, 13, and 11, respectively, preferably by soldering the same thereto as in the case of the portion 29. In each instance, the flat surface of the tubular member is placed against the wall to which it is secured. The portion 29 extends forwardly of the front wall of the casing 17, where it is turned, as at 34, to lie substantially in the plane of the end of the portion 33 and substantially parallel to the wall 11, being communicatively connected to the control device 24. The portion 29 provides a downflow leg and the portions 30, 31 and 32 together with the device 24 provide an upflow leg of the system. The tubular member of system 26 also includes a downflow leg and with the device 24 an upflow leg, being, however, secured to the casing wall 23 and to the wall of compartment 28, and therefore the primes of reference characters applied to the conduit portions of system 25 designate like portions of the system 26.

The device 24 comprises a hollow body 24', preferably substantially cylindrical and closed at its lower end by a bottom wall 35, see Fig. 3. Through the bottom wall 35 there is an inlet aperture or port 36 into which is screw-threaded and sealed a T fitting, or the like, 37. The arms of the fitting 37 receive the conduit end portions 33 and 33' which are communicatively sealed thereto by sleeve nuts 38. The chamber 39, within the body 24' and into which the port 36 opens, is provided with oppositely directed outlet ports 40 in its side walls. The ports 40 are positioned above the bottom wall 35 and are provided with tubular fittings 41 to which the conduit portions 34 and 34' are respectively connected and sealed by sleeve nuts 42. The portions 34 and 34' extend substantially horizontally from the outlets 40 so that these portions together with the outlet ports 40 define high points or elevated portions in the systems 25, 26. Within the chamber 39 there is a plunger or piston 43 carried by a stem 44 rigidly secured, as at 45, to an internally threaded sleeve member 46. The member 46 is provided with external, longitudinally extending splines or ribs 47 which extend into longitudinal grooves 48 in a bonnet member 49 so as to prevent rotation of the sleeve member 46. The bonnet member 49 is screw-threaded, as at 50, into the open top end of the body 24'. The sleeve 46 is longitudinally adjustable and reciprocable by means of a screw member 51 threaded within the bore of the sleeve 46 and carried by a rotatable operating member 52. The member 52 has an externally screw-threaded portion 53 having threaded engagement with internal screw-threads in a hollow boss 54 depending within the bonnet 49. Upon the bonnet 49 there is a hollow extension 55 through which the operating member 52 extends. The bore of the extension 55 provides a packing material receiving recess, containing packing material 56 which is held in position by a coil spring, or the like, 57. A hollow cap member 58 is screw-threaded onto the end of the extension 55 and engages the end of the spring 57 to hold the same under compression. The operating member 52 serves as an adjusting stem for the plunger 43 and extends through an aperture 59 in the cap member 58. The free upper end of the operating member 52 may be provided with a polygonal portion 60 to receive a key or operating handle by which the member 52 may be rotated. The cover member 7 is preferably provided with an aperture 61 to receive the extension 55 and through which the operating member

52 is accessible for adjustment. The cover member 7 is also provided with openings 62 which align with the compartments 27, 28 for access thereto, and which may be closed by cover plates 63. The open top of the casing 17 registers with an opening 64 through the cover member 7, this opening being closable by a cover plate 65. The casing 17 is preferably surrounded by insulating material 66 within which portions of the circulating system conduit members and the device 24 are embedded. The insulating material 66 preferably extends between the front and rear walls 11, 12, and is positioned between transversely extending partitions 67, 68 which also serve to form side walls for the compartments 27, 28. It may be noted that the circulating system conduit members serve to support the device 24 in operative position. The conduit systems and the chamber 39 are filled with an expansible and contractible liquid, such as alcohol, to a level in the chamber 39 which is above the outlets 40 and to some such level as the line L—L, when the plunger 43 is in raised position and the apparatus is at room temperature.

The operation of my apparatus is as follows: A refrigerating medium such, for example, as carbon dioxide ice is placed within the casing 17 through the filling opening 64 which is then closed by the cover plate 65. The sublimation of the CO₂ ice within the casing 17 reduces the temperature therein and of the casing walls to a very low point and serves to abstract heat from the liquid within the conduit portions 29, 29' in contact with the extending surface provided by walls 22, 23, respectively. The abstraction of heat results in an increase in the density of the liquid in the portions 29, 29' and starts circulation of the liquid in the circulating systems 25, 26 in the direction indicated by the arrows, Fig. 2. The cold or cooled liquid moving through the portions 30, 31, and 32, and through the portions 30', 31', and 32', which are in intimate heat absorbing relation to the liner walls, serves to abstract or absorb heat from the compartments 27 and 28. The liner walls provide extended heat absorbing surface for the upflow legs of the systems 25 and 26. As the liquid in the systems 25 and 26 circulates, entering the chamber 39 through the port 36 and leaving via the ports 40, the flowing liquid will carry away heat from the compartments 27 and 28 thereby reducing the temperatures therein. As the temperature of the compartments drops, the heat content of the liquid will also decrease and the volume of the liquid in the systems will contract, causing the level of liquid within the chamber 39 to drop below the line L—L. This contraction of the liquid which is in accordance with the heat content thereof will continue as the temperature of the compartments 27, 28 decreases, due to abstraction of heat from the circulating fluid by the carbon dioxide ice in the casing 17, until the systems are in balance or until the level of the liquid drops below the high point of each system, preferably the bottom edges of the outlet ports 40. As soon as the level drops below the system high points defined by the ports 40, the continuity of the liquid path will be broken and circulation of the liquid through the systems will cease. If the temperature within the box 1 should increase after circulation has been reduced or stopped, the liquid in the systems 25, 26 will expand due to increase in the heat content of the liquid and either increase the rate of flow or again start circulation of the liquid, as the case may be.

Control of the temperature within the box 1 may be obtained by the plunger 43. Downward movement of the plunger 43 by rotation of the operating member 52 will increase the quantity or 5 volume of liquid above the bottom edges of the ports 40 due to displacement of the liquid in the lower portion of the chamber 39. This increase in the quantity of liquid above the system high points will require a greater reduction in the 10 temperature of the box chambers 27, 28 in order to result in sufficient contraction of the liquid to reduce the liquid volume to bring the liquid level below the ports 40. It is obvious that the greater 15 the displacement of liquid within the chamber 39 below the ports 40 by the plunger 43, the lower the temperature will have to drop in the compartments 27 and 28 in order to obtain sufficient contraction of the liquid to bring the level thereof below the ports 40.

20 In Fig. 4, I have shown another form of control device, comprising a substantially cylindrical casing 69 closed at its top and bottom ends and having an inlet 70 through its bottom wall. The inlet 70 opens upwardly through the bore of a 25 sleeve portion or overflow tube 71. The top or overflow edge 72 of the portion 71 defines the high point of the system and the cut-off point for liquid circulation. The interior of the casing 69 is provided with outlet ports 73, the lower edges 30 of which are below the inlet overflow edge 72 and which are connected to the conduit member portions 34, 34'. The inlet 70 is connected by a 35 nipple 74 to a fitting 75 having oppositely directed inlet ports 76 for connection to the conduit member portions 33, 33'. The fitting 75 has its interior in communication through a nipple 77 with a chamber 78 within a casing member 79. Positioned within the chamber 78 there is a longitudinally expandable and contractible metal 40 bellows 80 which is closed at its inner end by a head member 81. A coil spring 82 is positioned within the chamber 78 and is interposed between the end wall of the chamber 78 and the end wall of the bellows member. At its other end, the bellows member 80 is provided with a lateral flange 83 which overlies the end face of the casing wall to close and seal the chamber 78. The flange 83 is held in position by a cover member 84 which is 45 screw-threaded onto the casing 79, as at 85. The central portion of the cover member 84 is provided with a transversely extending sleeve portion 86 having an internally screw-threaded bore 87. Adjustably screw-threaded in the bore 87 there 50 is an adjustment rod 88 which seats at its inner end against an abutment member 89 rigid with the bellows head 81. The member 88 is retained within the bore 87 by a cap member 90 which is 55 screw-threaded onto the portion 86. The member 88 preferably extends through an aperture 91 in the member 90 and is provided at its outer free end with a polygonal portion 92 by which the member 88 may be longitudinally adjusted.

It is believed that the operation of the refrigerating apparatus, when provided with the control device of Fig. 4, will be obvious from the foregoing description of the apparatus when provided with the control device of Fig. 3. When the apparatus provided with the device of Fig. 4 is placed in operation, the alcohol or other liquid will fill the chamber 78 around the bellows 80. Adjustment of the point at which there will be sufficient contraction of liquid to reduce its volume below the overflow point 72 may be accomplished by varying the capacity of the cham-

ber 78 by means of the adjustment member 88 and the bellows 80.

What I claim and desire to secure by Letters Patent of the United States is:

1. A refrigeration apparatus including a compartment to be refrigerated, a continuous conduit member having a portion thereof in heat exchange relation to said compartment, a liquid in said conduit member establishing a closed liquid circuit and operable to abstract heat from said compartment at said portion, means to abstract heat from said liquid at another portion of said conduit member, said liquid being expandable and contractible in accordance with the heat content thereof, said conduit member having a high point effective upon contraction of the liquid to interrupt the liquid circuit, and means to vary the level of said liquid above said high point. 5

2. A refrigeration apparatus including a compartment to be cooled, a container for refrigerant medium, a continuous conduit member having one portion in direct heat exchange relation with said container and having another portion in direct heat exchange relation with said compartment, an expandable and contractible liquid in 10 said conduit member adapted to circulate through said conduit member due to difference in temperature of the liquid at said container and at said compartment, said conduit member having a high point 15 effective upon contraction of said liquid due to drop of temperature in said compartment to interrupt liquid circulation, and means for regulating the level of the liquid above said high point whereby to control the temperature of said compartment. 20

3. A refrigeration apparatus including a compartment to be cooled, a heat conducting container in said compartment for refrigerant medium, a continuous conduit member having one portion in direct heat conducting relation with said container and having another portion in direct heat exchange relation with said compartment, means providing extended heat absorbing surface for said other conduit member portion and disposed in said compartment, an expandable and contractible liquid in said conduit member 25 adapted to circulate through said conduit member due to difference in temperature of the liquid at said container and at said compartment, and said conduit member having a high point effective 30 upon contraction of said liquid due to drop of temperature in said compartment to interrupt liquid circulation. 35

4. A refrigeration apparatus including a compartment to be cooled, said compartment having heat insulated walls and a metal liner, a container for refrigerant medium positioned within said compartment, means insulating said container from said compartment, a continuous conduit member having one portion secured against said liner and having another portion secured to and against the wall of said container, an expandable and contractible liquid in said conduit member adapted to circulate through said conduit member due to difference in temperature of the liquid at said container and at said compartment, and said conduit member having a high point effective upon contraction of said liquid due to drop of temperature in said compartment to interrupt liquid circulation. 40

5. A refrigeration apparatus comprising a container having a metal wall and adapted to contain a refrigerant medium, a continuous conduit member having one portion in intimate heat exchange relation with said metal wall, said con-

70
75

- duit member having another portion spaced from said metal wall and operable to absorb heat, and an expansible and contractible heat transferring liquid in said conduit member adapted to circulate through said conduit member due to difference in temperature at said portions, said one portion including a high point in said conduit member effective to regulate circulation of the liquid in response to variation in the volume of the liquid.
6. A refrigeration apparatus including a compartment to be cooled, said compartment having heat insulated walls and a metal liner, a container for refrigerant medium positioned within said compartment, said container having a metal wall, means insulating said container and said wall from said compartment, a continuous conduit member having one portion secured against said liner and having another portion secured to said metal wall, an expansible and contractible liquid in said conduit member adapted to circulate through said conduit member due to difference in temperature of the liquid at said container and at said compartment, and said conduit member having a high point effective upon contraction of said liquid due to drop of temperature in said compartment to interrupt liquid circulation.
7. A refrigeration apparatus comprising a container having a metal wall and adapted to contain a refrigerant medium, a continuous conduit member having one portion in heat conducting relation with said metal wall, said conduit member having another portion spaced from said metal wall and operable to absorb heat, an expansible and contractible heat transferring liquid in said conduit member adapted to circulate through said conduit member due to difference in temperature at said portions, said one portion including a high point in said conduit member effective to regulate circulation of the liquid in response to variation in the volume of the liquid, and means to regulate the level of said liquid above said high point.
8. A refrigeration apparatus including a circulatory system, means to abstract heat from said system at one portion thereof, said system having another portion operable to absorb heat from a compartment to be cooled and disposed within said compartment, said system containing a liquid adapted to circulate due to difference in temperature between said portions and operable to convey the absorbed heat to said heat abstracting means, said liquid being expansible and contractible in accordance with variations in the heat content thereof whereby to vary the volume of the liquid in said system, flow controlling means establishing a high point in the system determining the extent of contraction in the liquid volume which will break the liquid circuit thereby to stop circulation, said system including a variable capacity chamber, and means to vary the capacity of said chamber whereby to vary the level of the liquid in said system above said high point to correspondingly vary the temperature to be maintained in said compartment.
9. A refrigeration apparatus including a circulatory system, means to abstract heat from said system at one portion thereof, said system having another portion operable to absorb heat from a region to be cooled, said system containing a liquid adapted to circulate due to difference in temperature between said portions and operable to convey the absorbed heat to said heat abstracting means, said liquid being expansible and contractible in accordance with variations in the heat content thereof whereby to vary the volume of the liquid in said system, flow controlling means

establishing a high point in the system determining the extent of contraction in the liquid volume which will break the liquid circuit thereby to stop circulation, said system including a variable capacity chamber positioned below the low liquid level in said system, a bellows member closing and sealing one side of said chamber, and means to adjust said bellows member whereby to regulate the volumetric capacity of said chamber and thereby to control the level of liquid in said system relative to said high point.

10. A refrigeration apparatus including a circulatory system, means to abstract heat from said system at one portion thereof, said system having another portion operable to absorb heat from a region to be cooled, said system containing a liquid adapted to circulate due to difference in temperature between said portions and operable to convey the absorbed heat to said heat abstracting means, said liquid being expansible and contractible in accordance with variations in the heat content thereof whereby to vary the volume of the liquid in said system, flow controlling means establishing a high point in the system determining the extent of contraction in the liquid volume which will break the liquid circuit thereby to stop circulation, said system including a casing member having an opening in one wall thereof for communication of the interior of said casing member with the liquid in said system, a bellows member within said casing member and having one end secured and sealed to said casing member, a wall closing and sealing the other end of said bellows member, means engaging said wall to expand said bellows member whereby to decrease the liquid containing capacity of said casing member, and a spring opposing expansion of said bellows member.

11. Refrigerating apparatus comprising a cabinet having a compartment for the storage of food to be refrigerated, a liquid circulatory system in said cabinet, means to abstract heat from said system at one portion thereof, said system having another portion disposed in said compartment for absorbing heat therefrom, a heat transferring solid liquid in said system adapted to circulate therethrough due to difference in temperature between said portions to maintain a substantially constant temperature in said compartment, the circulatory liquid conveying the heat absorbed thereby to said heat abstracting means, said liquid being expansible and contractible in accordance with variations in the heat content thereof whereby to vary the volume of the liquid in said system, said system including an elevated portion effective in accordance with the volume of said liquid to control circulation of the liquid in the system, and means operable to vary the level of said liquid between predetermined range limits and relative to said elevated portion to correspondingly vary the temperature to be maintained in said compartment.

12. Refrigerating apparatus comprising a cabinet having a metallic liner forming a food storage compartment to be refrigerated, a metallic container for a refrigerant medium positioned in and heat insulated from said compartment, a liquid circulatory system within said cabinet, said system having one portion in heat transfer relation with said metallic container and having another portion in heat conducting relation with said metallic liner, said metallic liner constituting an extended heat absorbing surface of said last-named portion for absorbing heat from said food storage compartment, and a heat transfer-

- ring liquid in said system adapted to circulate therethrough due to difference in temperature between said portions to maintain a substantially constant temperature in said compartment, the 5 circulatory liquid conveying the heat absorbed thereby to said metallic container for abstraction by the refrigerant medium therein, said liquid being expansible and contractible in accordance with its heat content whereby to vary the volume 10 of the liquid in said system, said system including an elevated portion effective in accordance with the volume of said liquid to control circulation of the liquid in the system.
13. Refrigerating apparatus comprising a cabinet having heat insulating walls defining a compartment, a container for containing a refrigerant medium and disposed in said compartment between opposite walls thereof providing chambers between the walls of said container and said 15 opposite walls of the cabinet, conduit means providing a liquid circulatory system and disposed within said compartment, said conduit means being in heat transfer relation with said container and having a portion thereof extending into one 20 of said chambers for absorbing heat therefrom, conduit means providing a second liquid circulatory system and disposed within said compartment, said second-named circulatory system being in heat transfer relation with said refrigerant container and having a portion extending into another of said chambers for absorbing heat 25 therefrom, a heat absorbing liquid in said systems for absorbing heat from said chambers for transfer to said refrigerant medium, said liquid being circulative through said systems due to the difference in temperature between the refrigerant 30 container and the chambers to be refrigerated, said liquid being expansible and contractible in accordance with its heat content whereby the volume of the liquid in said systems varies, and a header member disposed within said compartment adjacent said container and into which the opposite ends of each of said conduit means connect at vertically spaced points, said header member having an overflow high point for the liquid of both systems 35 for controlling circulation of the liquid.
14. Refrigerating apparatus comprising a cabinet having heat insulating walls defining a compartment, a container for containing a refrigerant medium and disposed in said compartment between opposite walls thereof providing chambers between the walls of said container and said opposite walls of the cabinet, conduit means providing a liquid circulatory system and disposed within said compartment, said conduit means being in heat transfer relation with said container and having a portion extending into one of said chambers for absorbing heat therefrom, conduit means providing a second liquid circulatory system and disposed within said compartment, said second-named circulatory system being in heat transfer relation with said refrigerant container and having a portion extending into another of said chambers for absorbing heat therefrom, a heat absorbing liquid in said systems for absorbing heat from said chambers for transfer to said refrigerant medium, said liquid being circulative through said systems due to the difference in temperature between the refrigerant container and the chambers to be refrigerated, said liquid being expansible and contractible in accordance with its heat content whereby the volume of the liquid in said systems varies, and a header member disposed within said compartment adjacent said container and into which the opposite ends of each of said conduit means connect at vertically spaced points, said header member having an overflow high point for the liquid of both systems for controlling circulation of the liquid.
15. A refrigeration apparatus comprising a container having a metal wall and adapted to contain a refrigerant medium, a continuous conduit member having one portion in intimate heat exchange relation with said metal wall, said conduit member having another portion spaced from said metal wall and operable to absorb heat, an expansible and contractible heat transferring liquid in said conduit member adapted to circulate through said conduit member due to difference in temperature at said portions, and a header member connected in said circulatory system and providing a high overflow point for controlling the circulation of the liquid.

LEWIS W. EGGLESTON.
